UNITED STATES PATENT OFFICE.

RALPH V. L. HARTLEY, OF SOUTH ORANGE, NEW JERSEY, ASSIGNOR TO WESTERN ELECTRIC COMPANY, INCORPORATED, OF NEW YORK, N. Y., A CORPORATION OF NEW YORK.

SECRET SIGNALING.

Application filed September 8, 1920, Serial No. 408,890. Renewed November 14, 1925.

To all whom it may concern:

Be it known that I, RALPH V. L. HARTLEY, a citizen of the United States, residing at South Orange, in the county of Essex, State 5 of New Jersey, have invented certain new and useful Improvements in Secret Signaling, of which the following is a full, clear, concise, and exact description.

The present invention relates to secret 10 transmission of electrical currents or waves for signaling or other purposes.

More specifically the invention relates to the type of wave transmission in which a sustained wave is modulated or controlled 15 in accordance with the wave to be secretly transmitted. A sustained wave used in this manner is sometimes called a carrier wave, and generally has a constant high frequency. In the present invention, however, the carrier 20 wave may be audible and is made to have a cyclically varying frequency, the rate of variation being very low in comparison with the frequency of the signaling waves to be transmitted.

It is an object of the invention to enable 25 audio frequency currents representing intelligence, but having a form which renders them unintelligible when received by ordinary means, to be efficiently transmitted 30 to the practically complete exclusion of components which are unnecessary and which might tend to lessen the difficulty of obtaining intelligible indications from the transmitted currents.

It is well known that when a carrier wave 35 is modulated by a range of low frequency waves such as speech waves, a number of different frequency components result, among which are an unmodulated component of the original carrier frequency and two sidebands representing the sum and difference, respectively, of the carrier frequency and the speech frequencies. If all 40 of these components are transmitted over a telephone line, the speech frequency can be received by the use of a simple detector. If the unmodulated carrier frequency component is completely suppressed and only 45 one sideband is transmitted, it is impossible to receive the speech by simple detection, but

if a wave of the carrier frequency is combined at the receiver with the transmitted sideband, a detector will yield the speech waves. A system in which only one sideband is transmitted, therefore, possesses a 55 considerable degree of secrecy, since an outsider would have some difficulty in discovering the frequency of the wave which it is necessary to use at the detector in order to receive speech. It is conceivable, however, that one might hit upon the proper frequency by trial, and when once this has been discovered there would be but little difficulty in receiving the speech.

It has been proposed to use a continuously 60 varying carrier frequency in order to make it necessary to know not only the carrier frequency at any instant, but the manner in which it is varied before the transmitted message can be received. By varying the 65 carrier frequency over a considerable range, and especially by employing a more or less complex scheme of variation of the carrier frequency, a high degree of secrecy is obtainable.

If a wire transmission system is used, it is desirable to suppress completely the currents of the original voice frequencies, since 70 if any of these get to the line it might be possible to filter them out and amplify them sufficiently to render them receivable. It is also necessary to suppress practically 75 completely the unmodulated carrier frequency component and one of the sidebands.

It is desirable also to suppress double frequency components and the other frequency components which are not to serve any useful purpose. If the lower sideband is the one which is to be transmitted, and if the lowest essential frequency represented in it 80 is above the highest voice frequency, then a high pass and a low pass filter in series in the output of the modulator can be used. The high pass filter will suppress all currents of the frequencies from zero up to 85 the upper limit of the voice range, while the low pass filter will suppress all currents of frequencies higher than the lower sideband including components of the carrier frequency and the harmonics. If the lower 90

100

sideband, however, contains frequencies so low as to overlap the voice range, a filter cannot be used to suppress the voice, but a balanced modulator may be used for this purpose as will be described hereinafter. In either case a low pass filter may be used to suppress the unmodulated carrier component, the upper sideband and the high harmonics. It will be shown hereinafter, however, that if a low pass filter having a fixed cutoff frequency is used to suppress the carrier it will permit of only a very limited range of variation of the carrier frequency.

It is a further object of the present invention to overcome this limitation and to make possible a variation of the carrier frequency over any desired range while still preventing the unmodulated component of carrier frequency and other undesired frequency components from being transmitted. In the present instance, this object is accomplished by varying simultaneously with the carrier frequency the frequency above which all frequencies are suppressed. This may be done either by the use of a plurality of filters of successively higher cutoff frequencies or by a filter having a variable cutoff.

In the drawings to which reference will now be made for a more detailed description of the invention, Figs. 1, 2, 3 and 4 are schematic circuit diagrams illustrating forms of embodiments which the invention may take. Fig. 1^a is a graphic representation of certain frequency relations made use of in describing the invention, Fig. 2^a illustrates a modification of certain details of Fig. 2, and Fig. 5 shows a modified form of filter suitable for use in the system of the invention.

In the system to be described, it is assumed that the carrier frequency varies cyclically in any desired manner between the limits v and $v+d$ where d varies between zero and a predetermined limiting value. If the speech frequency band as a whole is represented by s and if the carrier wave is modulated by currents of speech frequencies, as will be assumed in the present case, the resulting components will be of frequencies $v+d-s$, $v+d$, and $v+d+s$. If the lower band of frequency $v+d-s$ alone is to be transmitted, an upper limiting or low pass filter will be used to enable the band $v+d-s$ to be transmitted but to suppress the higher frequency components including both the unmodulated carrier component and the upper sideband. This means that the cutoff frequency of the filter must always lie between the carrier frequency $v+d$ and the frequency in the band $v+d-s$ lying nearest to the carrier frequency. The permissible range of variation of the carrier frequency is limited, therefore, to something less than the lowest essential

voice frequency. This is illustrated in Fig. 1^a. The upper portion of the diagram represents the position of the speech modulated wave in terms of frequency relative to the cutoff frequency F of the filter at the instant when the carrier frequency has been varied to its upper permissible limit ($d=\text{max.}$) and the lower portion of the figure represents the conditions at the instant when the carrier frequency has its lowest frequency value ($d=0$). The carrier frequency is in this figure denoted by the heavy vertical line. The sidebands are denoted by s , the one to the left of the carrier frequency being assumed to be the lower and the one at the right the upper sideband. If the filter is so designed that all frequencies to the left of the cutoff frequency F of the filter are transmitted while all frequencies to the right are suppressed, it is seen that in both extreme conditions i. e. $d=0$ and $d=\text{max.}$, the lower sideband is transmitted but the carrier and the upper sideband are suppressed. If the carrier should be varied to a higher limit than that shown by $d=\text{max.}$, it will be seen, bearing in mind that the sidebands would be shifted with the carrier, that some of the lower sidebands would be thrown into the suppression range of the filter and this would result in impairing the transmission of the speech. If the carrier goes to a lower value than that indicated by $d=0$, it will pass into the transmission range of the filter. It is evident therefore that with a filter having a fixed cutoff, the maximum permissible range of variation of the carrier frequency is somewhat less than the frequency interval between the carrier and the nearer edge of the sideband.

According to the present invention, the cutoff frequency F is changed with the carrier so that to whatever extent the carrier frequency shifts, the cutoff frequency changes in such a manner as to suppress the carrier, but to permit the transmission of one of the sidebands. One arrangement for accomplishing this is shown in Fig. 1. In this figure a transmitting arrangement is shown. The modulator M is supplied with carrier oscillations from the generator O and with speech frequencies from the circuit 2. The speech waves originate in the microphone circuit 3, which is coupled to the circuit 2 through a low-pass filter 4. This filter is so designed as to transmit all of the essential voice frequencies, but to suppress the high harmonics of the voice so that essential speech frequencies confined to a limited range are used to modulate the carrier. The modulator M is of the balanced type comprising the two discharge devices 5 and 6 connected so as to suppress transmission of the speech waves. The speech waves, it will be noted, are impressed

upon the common connection between the filaments and the grids through the coil 7, while the carrier wave from the oscillator O is impressed in an opposite sense upon the two tubes by means of the coupling 8. Due to the mode of connection employed here, the unmodified voice frequency components are suppressed, but the unmodified carrier component will be transmitted. The carrier frequency may be high in comparison with speech frequencies but it may also be of audible frequency. There will be no confusion of the original speech currents and the side band currents for the reason that the former are not transmitted by modulator M.

A filter 9 is employed to suppress the carrier frequency, but to permit the transmission of the lower sideband resulting from modulation of the carrier by the speech frequency currents. The filter 9 is, as is also the filter 4, of the general type described in the patent to Campbell, No. 1,227,113, dated May 22, 1917, but filter 9 is provided with means for making its upper limiting frequency variable at will. The filter 9 comprises a number of sections each of which includes inductive elements in series with the line and capacitative elements in shunt of the line. The cutoff frequency of the filter depends upon the product of the inductance and the capacity values, and hence by varying the magnitude of either the inductance or the capacity, it is possible to vary the cutoff frequency. In the drawing, the capacity in shunt of the line consists of fixed capacity elements 10 and variable capacity elements 11 in parallel with each other. The variable capacity elements each comprise a stationary plate and a rotatable plate which is arranged to be driven by the motor 12, and their plates or armatures may be so designed as to introduce any desired changes into the capacity of these condensers. In this way the cutoff value of the filter may be varied in any one of a number of ways by changing the shape and size of the condensers even though the speed of rotation of the motor remains the same. As pointed out above, the carrier frequency in this system changes cyclically between predetermined limits. For introducing these frequency variations the oscillator O may be supplied with a cyclically varying capacity element 13 mounted on the same shaft as the condensers 11, and the system may be so controlled that as the carrier frequency, supplied from the oscillator O, increases or decreases, the cutoff value of the filter will follow the changes in the carrier frequency by virtue of the variations in capacity of the condensers 11. With an arrangement of this kind it is possible to vary the carrier frequency in accordance

with any desired scheme of variation between relatively wide limits, and still permit the transmission of the lower sideband, but suppress the transmission of the unmodulated component of the carrier frequency. 70

Since in order to receive the wave transmitted from the circuit in Fig. 1, it is necessary to supply to the detector a wave of the carrier frequency, it is necessary to provide at the receiver an oscillator, the 75 frequency of which varies in the same manner as that of the oscillator O. This may be done conveniently by providing at the receiver a constant speed motor similar to 12 and by synchronizing the movements of 80 the two motors in any well known manner.

For two-way secret communication, a receiver may be provided at the same station as the transmitter shown in Fig. 1, and this 85 receiver may be supplied with the necessary carrier frequency wave from the oscillator O provided the same carrier frequency is used for transmission in the two directions. The type of receiver necessary 90 will be clear, it is believed, from the description that has been given of the transmitting circuit, but the circuit arrangement preferably used at the receiver will be described more in detail in connection 95 with Fig. 3.

The system of secret signaling according to the invention may be either simplex or multiplex. Fig. 2 shows a schematic layout of a terminal station on the multiplex line 14, in which provision is made for transmitting simultaneously two messages in each direction. By an extension of the arrangement illustrated in this figure it is 100 evident that a larger number of channels may be provided. The multiplex line 14 has a balancing network 15 by virtue of which in connection with the hybrid coil 16, 17, currents may be impressed on the line 105 and received from the line without interfering with one another. Bridged across the line 14 is a transmitting loop S to which the transmitting circuits of all of the channels are connected, and inductively related to the hybrid coils 16, 17 is a receiving 110 loop R to which the receiving circuits of the channels are connected. In this system instead of showing a transmitter and receiver connected with the modulator and detector, low frequency lines such as ordinary telephone lines L₁ and L₂ are connected with the high frequency sets to enable two-way repeating between the multiplex line and the telephone lines. Each 115 channel is supplied with carrier frequency oscillations from the generators such as indicated at O₁ and O₂. The voice currents received over the line L₁, for instance, are impressed upon the modulator M₁ in the 120 same manner as indicated in Fig. 1, and the 125 130

carrier wave from the oscillator O_1 is modulated in accordance with speech or other low frequency currents transmitted over line L_1 . A transmitting filter SF_1 , which 5 may be of the type shown in Fig. 1, suppresses transmission of the unmodulated carrier frequency component, but permits transmission of the lower sideband from the modulator to the line through sending 10 loop S . At the same time speech currents received over the line L_2 modulate a carrier wave of a different frequency from oscillator O_2 by means of the modulator M_2 , and the lower sideband of this modulated 15 carrier frequency wave is selectively transmitted to the line. Still other low frequency lines might be associated in a similar manner with the multiplex sets.

At the distant station of the line 14, these 20 sidebands will be received in suitable apparatus including means for detecting the speech or other low frequency components by which the carrier currents were modulated. Since the distant station of the line 25 may be similar in every respect to that shown in this figure, the nature of the receiving circuit may be understood by reference to the receiving apparatus at the terminal station shown. It will be assumed 30 that waves of the same carrier frequency are used for transmitting in the two directions and that the lower sideband is in each case transmitted, although if preferred, the upper sideband could be transmitted, and 35 different carrier frequencies for the two directions might be used. Modulated waves received from the line 14 in the loop R and intended for the low frequency line L_1 are selectively received by the receiving filter 40 RF_1 , from which they pass into the detector D_1 . As pointed out above, it is necessary to supply to the detector a carrier wave component of the same nature as that which 45 was modulated at the distant station by the message wave to be detected, but of which the unmodulated component was suppressed at the distant station. This wave may be introduced to the detector D_1 from the oscillator O_1 , as is shown. In the same manner 50 modulating waves to be retransmitted over the line L_2 are selectively received by the receiving filter RF_2 , and are detected by the detector D_2 . The receiving filters, the transmitting filters and the oscillators may be 55 controlled cyclically by the motor 12 in the same manner as that indicated in Fig. 1. As stated above, a similar motor and similar high frequency apparatus will be provided at the distant station of the line, and as it 60 is necessary to maintain synchronism between the shafts which drive the high frequency apparatus at the two stations, any suitable method of synchronizing may be employed. For purposes of illustration, 65 however, an impulse sender 18 is shown com-

prising a brush arm connected to the shaft of the motor 12, and arranged for making contact successively in its rotation with the commutator segments 19. These contacts close a circuit from battery 20 through the low-pass filter LP , the sending loop S and the main line 14. The low-pass filter LP prevents waves of carrier frequency from finding access to the commutator circuit, but permits the transmission of periodic impulses to the main line 14. The commutator may be arranged to transmit any number of these impulses per revolution of the motor, four such impulses being transmitted in the arrangement shown. At the distant station these impulses are received through a filter similar to LP and may be used in accordance with any one of a number of well known synchronizing systems for introducing phase corrections into the motion of a synchronously driven shaft which may control the oscillators and the filters at that station. It should be noted that these impulses bear no definite relation to the carrier frequencies or to the scheme of variation of the carriers, since any desired number of correcting impulses may be transmitted per revolution, and the condensers which control the oscillators and the filters may be given any desired shape and may be changed from time to time. It is evident, therefore that the correcting impulses will give no clue to the conditions that it is necessary to know in order to receive the message, and that the correcting impulses do not need to be concealed.

The filter that is preferably used in the circuits thus far shown, is a low-pass filter which transmits freely currents of all frequencies between zero and a predetermined upper limit. If the system is used on a multiplex line, as indicated in Fig. 2, the filters of the different channels will differ as to their cutoff frequencies and the filter having the highest cutoff frequency of any of the channels will admit the frequencies transmitted by the other channels. To prevent the possibility of cross-talk, band filters BF may be inserted between the variable filters and the line. These filters may be fixed filters of suitable constants to permit the passage of all frequencies that it is desired to transmit through the channel to which they are connected, but to suppress transmission of frequencies used by each of the other channels.

It has been assumed that the cutoff value of the filters that have been described is varied by varying the shunt capacity only. For most purposes this will probably be sufficient. However, the impedance of a filter whose cutoff frequency is varied in this manner, would also vary to a considerable extent. Since the expression for both the cutoff frequency and the impedance involve the

inductance and the capacity of the filter sections, it may be desirable in some cases to vary cyclically the inductance as well as the capacity in order to maintain the impedance 5 more nearly constant. A filter in which provision is made for doing this is indicated in Fig. 5, which in view of the other figures will be understood without further explanation.

10 It is, of course, possible to operate one or two channels of the multiple system of Fig. 2 with an audio frequency carrier wave. The first channel, might, for example, use the lower side band of a modulated carrier 15 wave of 2,500 cycles frequency and the second channel, the lower side band of a modulated carrier wave of 5,000 cycles frequency.

Fig. 2^a illustrates a modification of Fig. 2 in which a variable band filter having 20 variable series and shunt capacities may be used to replace a pair of filters such as SF₁ and BF or RF₁ and BF in each one-way channel. The characteristic of the filter of Fig. 2^a is such that the width of its transmission band may remain approximately constant as its upper and lower cut-off frequencies simultaneously increase or decrease. This type of filter is accordingly well 25 adapted to transmit a modulation side band 30 of fixed range, but of varying carrier frequency.

Instead of varying the cutoff frequency of the filters which are used to suppress the carrier frequency, arrangements are shown in 35 Figs. 3 and 4 for using a plurality of fixed filters having successively different cutoff frequencies.

In Fig. 3, the modulator M is supplied by the carrier wave from the oscillator O 40 and by speech waves from the circuit 22, as in the previous figures. The output of the modulator leads to rotating switch arms 23 arranged to connect the leads 24 of the modulator successively to the input terminals of the respective filters SF, SF' and SF''. The output sides of these filters are connected in parallel to the outgoing line 25. The switch arms 23 may be driven from the shaft of the motor 12, which also drives the 45 variable condenser 13 for introducing variations into the oscillator frequency. If the cutoff frequency of the successive filters differs by less than the frequency interval between the carrier and the near edge of the 50 side band to be transmitted, it is evident that as the carrier frequency rises to the point where the lower sideband is about to pass into the suppression range of the filter SF, the carrier frequency has exceeded 55 the cutoff value of the filter SF'. The filter SF can, therefore, be switched out of the circuit and the filter SF' can be thrown into the circuit and the carrier frequency can then be permitted to increase to such a high 60 value that the lower sideband is about to be

cut-off by this filter when the third filter SF'' may be switched in. This process may be continued indefinitely by providing enough filters. The switch arms 23 are provided with sufficiently broad contacts to enable the next succeeding filter to be included in the circuit before the one previously used is disconnected so that no discontinuity in the transmission occurs. As the carrier frequency decreases in value, the filters will be 70 switched into the circuit in the reverse order and any suitable means of controlling the switch arms 23 by the continuously rotating shaft of the motor 12 may be employed. It is considered unnecessary to 80 show further details of such an arrangement.

Referring now to the receiving circuit of Fig. 3, modulated incoming waves in the circuit 26 are impressed upon the bank of receiving filters RF, RF' and RF''. Switch arms 27 connected to the shaft of the motor 12 and operating in the same manner as switch arms 23, cut the successive receiving filters into and out of the line leading from 90 circuit 26 to the detector D. In the case of a simplex system it probably would not be necessary to use a plurality of receiving filters, provided arrangements were used for venting transmission of the carrier wave 95 back to the line. However, the three receiving filters have been indicated for purposes of illustration, since in a multiplex system it might be desired to have the frequencies of the currents of all the channels vary together in the same sense, so that at certain 100 instants the channel would be using currents of certain frequencies which at other instants might be used by a different channel, in which case it would be necessary to 105 provide receiving filters corresponding to the transmitting filters. The detector D may be of the type used in any of the circuits heretofore shown. It comprises two discharge tubes 28 and 29 connected in balanced relation, the received sideband being impressed upon the two grid circuits 110 through the coupling 30. The necessary unmodulated component of carrier wave frequency might be applied either to the input circuit or to the output circuit. It is preferably applied to the output or plate circuit, as is indicated by the connection 31, since such connection prevents transmission 115 of the carrier frequency back to the line 26 by virtue of the unilateral conductivity of the discharge devices 28 and 29. By taking these extra precautions in keeping the carrier frequency off from the line, a less rigid 120 condition is imposed upon the receiving filters. The detected low frequency or speech waves from the detector D pass into the circuit 32, which may lead to suitable receiving apparatus.

125 An alternative scheme of controlling the 130

carrier frequency and the cut-off frequency of the transmitting filters is indicated in Fig. 4. In this figure the dotted line 33 indicates the shaft of the motor such as motor 12 in the other figures. This shaft merely serves to drive the commutator 34 which is shown provided with conducting and insulating segments irregular in character. The shape and disposition of these segments determine the manner in which the carrier frequency is varied, and this affords a simple and convenient manner of introducing different schemes of variation into the carrier frequency, since a number of commutators differently made up may be provided and the change could readily be made from one to another. The commutator 34 by its rotation controls the closure of the circuit from battery 36 through the relay 37. When the relay armatures are in their retracted position, as at the instant represented in the drawing, the circuit is closed between the output of the modulator M through the filter SF. This circuit may be traced from the lead 38 of the modulator to the contact spring 39, relay armature 40 and lead 41 to one terminal of the filter SF and from the other terminal of the filter through the lead 42 to the opposite lead 43 of the modulator M. Relay armature 40 in its retracted position permits the closure of contacts 44 which close a shunt around a portion of the inductance 45 which inductance, together with the condenser shown, controls the period of the oscillator O furnishing carrier waves to the modulator M. The adjustment of the oscillator and the constants of the filter SF are arranged so that when the shunting contacts 44 are closed, the filter SF suppresses the unmodulated component of the carrier frequency and components of higher frequency but transmits the lower sideband. When the relay 37 is energized by closure of the circuit through a conducting segment of the commutator, its armatures are attracted and armature 40 shifts the circuit from the contact spring 39 to the spring 46, and immediately thereafter breaks the contact between the spring 39 and the armature 40. At the same time it separates the contacts 44, thereby removing the shunt connection from the inductance 45. The output of the modulator is now connected through conductor 38, contact springs 39 and 46, conductor 47 to one terminal of the filter SF' and from the other terminal of the filter to the opposite lead 43 of the modulator. The filter SF' is so designed that when the shunt through contacts 44 is broken and the corresponding variation is introduced into the frequency of the oscillator, this filter will suppress the unmodulated carrier frequency component and components of higher frequencies but will permit the transmission of the lower sideband.

By alternately making and breaking the circuit of relay 37, therefore, a sudden shift in the carrier frequency is produced and the filters are alternately controlled to suppress the unmodulated carrier frequency component and to transmit the lower sideband. Relay 37 is also shown as provided with an armature 48, and by a set of contacts and circuits similar to those controlled by armature 40, causes the receiving filters RF and RF' to be alternately included between the incoming circuit 49 and the detector D. As noted above, it may not in all cases be necessary or desirable to provide a plurality of receiving filters, but in some cases a single filter will suffice.

The circuit arrangements that have been illustrated and described are intended merely as representative of preferred embodiments of the invention, and it is obvious that many other arrangements are possible and will occur to those skilled in the art. The invention, therefore, is not to be construed as limited to the specific circuit arrangements that have been disclosed, but only by the scope of the appended claims.

What is claimed is:

1. In a signaling system, a source of carrier waves of continuously varying frequency, means to modulate said waves in accordance with signals to produce upper and lower side bands of frequency components, selective circuits for selectively transmitting a portion of said frequency components to the practical exclusion of all of the components in one of said side bands, and means coordinated with the said source of carrier waves for varying the selective range of transmission of said selective circuits in step with the variations in the carrier frequency to cause said selective circuits to suppress substantially the whole of the same side band at all frequencies of the carrier wave.

2. In a signaling system, a source of carrier waves of continuously varying frequency, means to modulate said wave in accordance with signals to produce upper and lower side bands of frequency components, selective circuits for selectively transmitting a portion of said frequency components to the practical exclusion of the unmodulated carrier frequency component and all of the components in one of said side bands, and means coordinated with said source of carrier waves for varying the selective range of transmission of said selective circuits in step with the variations in the carrier frequency to cause said selective circuits to suppress said carrier frequency and substantially the whole of the same side band components at all frequencies of the carrier wave.

3. In a signaling system a source of carrier waves of cyclically varying frequency, a modulator for modulating said waves in

accordance with signals to be transmitted, filtering circuits for suppressing the unmodulated carrier frequency component while permitting transmission of one of the side bands, and means for controlling said circuits to vary the limiting frequency between the transmitted and the suppressed ranges as the carrier frequency is varied.

4. A signaling system comprising transmitting and receiving stations, synchronously driven control members at said stations, means for producing a complex wave at a transmitting station, selective circuits at each station for selectively transmitting a portion of said wave and means under control of said synchronously driven control members for cyclically varying the frequencies of said wave and for varying the transmission characteristics of said selective circuits to transmit the corresponding portion of said complex wave at its different frequencies.

5. In a modulated wave transmission system including a wave transmitting medium, circuits for producing for transmission a modulated carrier wave, a plurality of filtering circuits arranged for connection between said wave producing circuits and the medium, having different cut-off frequencies, means for changing the carrier frequency and for simultaneously changing the connections of said filtering circuits between said wave producing circuits and the transmission medium to transmit substantially the same relative components of said modulated wave and to suppress substantially the same relative components of said modulated wave after the carrier frequency is changed as before.

6. The method of modulated carrier wave signaling in which the carrier wave is cyclically varied in frequency, which method comprises modulating the carrier wave of varying frequency in accordance with signals to produce side bands, producing cyclic variations in the carrier frequency of greater extent than one half the frequency interval separating said side bands, filtering the modulated waves to suppress the carrier and one of the side bands while freely transmitting the other, and shifting the suppression range of the filtering circuits simultaneously with the cyclical changes in the carrier frequency to enable separation between the carrier and side band to be suppressed and the other side band at all the values of the carrier frequency.

7. In modulated carrier wave transmission of signals comprising a band of frequencies lying between two finite frequencies neither of which is zero, the method of selecting one side band to the exclusion of the carrier component and the other side band notwithstanding variations in the carrier frequency of greater extent than that repre-

sented between zero and the lower limiting frequency of the signals to be transmitted, which method comprises filtering the modulated wave to separate one side band from the carrier component and the other side band, and varying the cut-off frequency of the filtering circuits in synchronism with the variations in carrier frequency to cause the cut-off frequency of the filtering circuits to be within the frequency interval separating the carrier frequency and the side band to be transmitted at all values of the carrier frequency.

8. The method of wave transmission, which comprises modulating a varying frequency carrier wave by a modulating wave to produce a modulated wave, suppressing from the resulting modulated wave components of a range of frequencies including the original carrier frequency, and causing the absolute value of the limiting frequency of the suppressed range to vary in accordance with the variation in the frequency of the carrier wave, whereby suppression of the said range of frequencies including the original carrier frequency may take place with a greater range of variation of the carrier frequency than would be possible with a fixed limiting frequency.

9. A transmission system comprising means for producing a carrier wave of varying audio frequency, modulating circuits for modulating said wave in accordance with audio frequency currents to produce resultant modulated waves of frequencies overlapping the range occupied by said audio frequency modulating waves, and means included in said modulating circuits for suppressing transmission of unmodified audio frequency modulating currents, while permitting transmission of said modulated waves.

10. In a secret signaling system, a line, a source of audio frequency carrier waves, a balanced modulator including input and output individual branches and a neutral input branch, a source of speech current waves, said source of speech current waves being associated with said neutral branch, said source of carrier waves being differentially associated with both input individual branches, said lines being associated differentially with both output individual branches, whereby the speech waves are prevented from being transmitted to line, said carrier waves being of such low frequency that the resulting modulated waves overlap in frequency the range occupied by said speech waves, and a low pass filter connected between said modulator and said line for selectively transmitting the lower side band from said modulating circuit, said filter suppressing transmission of the carrier wave component.

11. In a signaling system, a line, modulat-

ing circuits for producing a speech modulated carrier wave having frequencies overlapping the range occupied by the unmodified speech waves, said modulating circuits including means to suppress transmission to the line of the unmodified speech waves, and a low pass filter connected between said modulating circuits and said line for sup-

pressing transmission of currents of the carrier wave frequency and of higher frequencies. 10

In witness whereof, I hereunto subscribe my name this 1st day of September A. D., 1920.

RALPH V. L. HARTLEY.
